[57] CLAIM

The ornamental design for a cup engaging actuation lever for a beverage dispensing head, as shown and described.

DESCRIPTION

FIG. 1 is a top, front perspective view of a cup engaging actuation lever for a beverage dispensing head showing my new design;

FIG. 2 is an elevational front view thereof on a reduced scale;

FIG. 3 is an elevational right side view thereof on a reduced scale, the left side being the mirror image of the right side;

FIG. 4 is an elevational rear view thereof on a reduced scale; and

FIG. 5 is a bottom plan view thereof.
